UNITED STATES PATENT OFFICE.

JAMES MORRIS BROWN, OF PHILADELPHIA, PENNSYLVANIA.

SPOOL.

Application filed August 13, 1923. Serial No. 657,256

My invention relates to spools in which a tubular member is provided at its opposite ends with relatively short sleeve-like portions located interiorly thereof, which portions 5 constitute bearings for supporting the spool upon a spindle or the like, and in which also the opposite sheet-like end portions thereof are separately constructed and secured to the opposite ends of the tubular member in planes extending substantially at 10 right angles to the axis of the spool.

It is desirable that these end sheets be secured to the opposite ends of the tubular structure in such manner that they may not 15 be accidentally disconnected and also in such manner that they will not work or become loose.

It is, therefore, the principal object of the invention to provide novel means whereby 20 such end sheets may be permanently and rigidly secured to the opposite ends of the tubular structure.

It is a further object of the invention to provide novel means whereby the attachment 25 of the said end sheets to the opposite ends of the tube structure of the spool shall be stronger than heretofore has been the case in so far as I am aware.

To these and other ends my invention comprehends a construction and arrangement of parts as hereinafter fully described, particularly pointed out in the claims and as illustrated in the drawing in which I have shown a convenient form of embodiment thereof.

35 In the drawing:

Fig. 1 is a view partly in side elevation and partly in central longitudinal section of a spool constructed in accordance with my invention;

40 Fig. 2 is a transverse sectional view taken on the line 2-2 of Fig. 1;

Fig. 3 is a transverse sectional view taken on the line 3-3 of Fig. 1;

Fig. 4 is a transverse sectional view similar to that shown in Fig. 3 but showing a slight modification of the structure; and

Fig. 5 is a perspective view of one of the fastening devices employed for securing the end plates to the opposite ends of a tubular 50 member of the spool structure.

Referring to the drawing: 1 designates a tubular member constituting a part of a spool structure upon which string, cord, wire and the like are adapted to be wound.

55 Situated within the interior of the tubular member 1 at its opposite ends are short

sleeve-like portions 2 which are secured in place in any suitable manner. In order that the said sleeve-like portions 2 may be secured in place so as to positively prevent the 60 loosening and the removal thereof, I have not only cemented the exterior surfaces of the said portions 2 to the interior surface of the tubular member 1, as indicated at 3, but I have also inserted tacks or nails 4 through 65 the tubular member 1, which tacks or nails extend into the members 2. The outer ends of the sleeve-like members 2 should be flush with the outer ends of the tubular member 1, as is clearly shown in Fig. 1 of the drawing. 70

The sleeve-like members 2 constitute bearings for the spool in case the same is placed upon a spindle or the like.

The tubular member 1 is provided at its 75 opposite ends with flat end sheets 7 of disk-shape and in order to secure these sheets firmly, securely and permanently in place I have provided wire staples 10 the opposite legs of which extend inwardly intermediate 80 the sleeves 2 and the adjacent portions of the tubular member 1.

In the construction as shown I have provided or employed two of these staples, but it will be understood that an additional 85 number may be employed if desired. The intermediate cross portions of these staples are located upon the outer sides of the sheets or plates 7, as indicated. It will be noted that the inner ends of the sleeves 2 are 90 beveled, as indicated at 11. The inner ends of the opposite legs of the staples 10 are bent over the inner edges of the said sleeves and terminate against the beveled surfaces 11, as is clearly shown in the drawing. These bent 95 over ends 17 extend inwardly in substantially radial direction with respect to the tube and terminate outwardly or outside of the interior surface of the sleeves 2.

In the construction as shown in Fig. 1 the 100 opposite legs of the staples are shown as occupying grooves or notches 15 in the outer surfaces of the sleeve-like bearing members 2.

In Fig. 4 a modification using a reverse 105 arrangement is shown. The tubular member 1' is provided with longitudinal grooves 16 upon its inner surface. The legs of the staples 10 occupy positions in these grooves and the inner ends of the opposite legs of 110 these staples 10 are bent over the inner beveled edges of the sleeves 2'.

It will be understood, however, that my invention is not limited to the particular positions with respect to the sleeves 2 and the adjacent portions of the ends of the tubular member 1 which may be occupied by the opposite legs of the staples 10. It is desirable and preferable, however, that the opposite legs of a staple shall occupy positions intermediate the sleeves 2 and the adjacent end portions of the tubular member 1, and it is also desirable that the inner ends of the legs of the staple shall be bent as indicated at 17 so as to interlock with the inner ends of the sleeves 2.

15 It will be seen that by the employment of staples in which the cross portion thereof which connects the opposite side legs are situated exteriorly of and in contact with the end sheets of the spool structure, and in 20 which the inner ends of the opposite legs are bent inwardly and over the inner ends of the bearing sleeves and are interlocked therewith, an extremely strong, neat and durable structure is produced.

25 It will be understood that in the construction of spools embodying my invention I am not limited to the particular means shown for securing the sleeve-like parts 2 in position in the interiors of the opposite ends of 30 the tubular member 1, but the securing of the said sleeves within the opposite end portions of the tubular member may be effected in any desired or preferred manner which will insure against accidental disconnection 35 of the same from the said tubular member.

Spools embodying my invention may be constructed of any suitable material, but I prefer to construct the same of paste-board. In case paste-board is employed the outer 40 end sheets 7 should be subjected to a suitable treatment, such as subjecting the same to a bath of sulphur, Montan wax, or the like, which increases the density and also renders the same more rigid and resistant to external 45 forces which may be applied thereto. It will be understood, however, that any suitable material may be employed in the manufacture of spools embodying the invention.

Having thus described my invention, what 50 I claim and desire to secure by Letters Patent is:

55 1. A spool, comprising a cylindrical portion upon which string, cord, wire and the like are adapted to be wound, end sheets secured to the opposite ends of the said cylindrical member, and staples extending through said end sheets and interlocked with the opposite end portions of the said cylindrical member, the said staples being arranged in planes parallel to each other.

60 2. A spool, comprising a tubular member, sleeve-like members situated in the opposite

end portions of the said tubular member, end sheets situated at the opposite ends of said tubular member, and staples arranged in parallel relation to each other, the opposite legs of each of which extend through said end sheets and interlock with the said sleeve members. 65

3. A spool, comprising an intermediate tubular portion upon which string, cord, wire and the like are adapted to be wound, sleeve-like members situated within the opposite end portions of said tubular member, means for securing the said sleeve-like members in place within the said opposite end portions, end sheets at the opposite ends of the said tubular member, and staples the said staples being arranged in planes parallel to each other, the opposite legs of each of which extend through said end sheets and intermediate the said sleeves and the adjacent portions of the opposite ends of the said tubular member, the inner ends of the opposite legs of said staple being bent around and interlocked with the inner ends of the said sleeve-like members. 70 75 80

4. A spool, comprising a tubular member, sleeve-like members located in the interior of the opposite end portions of said tubular member, the inner ends of said sleeves being beveled outwardly, means for securing the said sleeves in position within the said tubular member, end sheets located at the opposite ends of said tubular member, and staples having their opposite legs extending through said sheets and inwardly of the said tubular member intermediate the opposite end portions thereof and the said sleeve-like members, the inner ends of the said legs being extended inwardly and terminating upon the outwardly beveled inner end portions of said sleeves. 90 95 100

5. A spool, comprising a tubular member, relatively short tubular members located in the opposite ends of said tubular member, said short tubular members being provided with exterior longitudinally extending grooves, means for securing the said relatively short tubular members in position, sheets of disk-shape secured in contact with the outer ends of the said tubular members, and staples in parallel relation to each other and having their opposite legs extended through the said sheets, the said legs extending inwardly and being situated within the said grooves and their inner ends extending transversely and being in engagement with the inner ends of the said relatively short tubular members. 105 110 115 120

In testimony that I claim the foregoing as my invention, I have hereunto signed my name this 1st day of August, A. D. 1923.

JAMES MORRIS BROWN.
